UNITED STATES PATENT OFFICE.

KENNETH J. UNWIN, OF WORCESTER, MASSACHUSETTS, ASSIGNOR TO CROMPTON & KNOWLES LOOM WORKS, OF WORCESTER, MASSACHUSETTS. A CORPORATION OF MASSACHUSETTS.

SIDE-SLIP WEFT DETECTOR.

Application filed November 21, 1927. Serial No. 234,585.

This invention relates to improvements in side slipping weft detectors and it is the general object of the invention to provide a simple weft detector of the type specified, 5 practically all the operating parts of which may be confined in a casing to protect the same from dust, lint etc.

In co-pending application Serial No. 200, 481 filed by Payne there is shown a detector 10 having side slipping yarn engaging members pivoted to a slide which is guided in a support. The forwardly projecting end of the detector element extends through one side of the casing to engage the controller. 15 It is an important object of my present invention to keep the forwardly extending end of the detector entirely within the casing and to project a portion of the controller into said casing where it may be engaged by 20 the detecting member at substantial weft exhaustion.

The detector member and sliding carrier therefor in the aforesaid application are held yieldingly in rear position by a compression spring received by complementarily 25 semicircular grooves formed in the top and bottom, respectively, of the casing. This compression spring is hindered in its free movements by contact with said grooves 30 and there is occasionally some inconvenience in assembling such a construction. It is therefore a further object of my invention to simplify the method of applying the yielding force to the detector to hold the 35 same in normal yarn engaging position.

It is a still further object of my present invention to extend the forwardly projecting end of the detector member and to provide the same with a plurality of notches 40 located at different distances from the pivot of the detector member so that a variety of tensions may be provided to enable the detector to effectively cooperate with yarns of different characteristics.

45 With these and other objects in view which will appear as the description proceeds, my invention resides in the combination and arrangement of parts hereinafter described and set forth in the claims.

50 In the accompanying drawings wherein one form of my invention is shown,

Fig. 1 is a top plan view of a detector made according to my present invention showing the same in engagement with a full

supply of weft, certain parts being in section,

55 Fig. 2 is a vertical section on line 2—2 of Fig. 1,

Fig. 3 is a vertical section on line 3—3 of Fig. 1, and

60 Fig. 4 is a view similar to Fig. 1 but showing the detector in contact with an insufficient supply of weft and moved to indicating position.

65 Referring to the drawings the stationary stand 10 has a vertical slot 11 therein which reciprocates an actuator lever 12 operatively connected to weft replenishing mechanism not shown but of substantially the same form as set forth in patent to Ryon No. 1,030,748. Said lever is given a downward movement 70 on each detecting beat of the loom and when such movement is interrupted a change in the operation of the loom is initiated.

75 Said stand has a platform 13 which supports the casing in which the detecting elements are mounted, said casing including a base or bed 14 and a cap 15. Said base is provided with a longitudinal groove 16 into which a portion 17 of the cap extends to cause said cap and base to register with each other. The casing members are also provided with an aligning slot 18 through which extends a securing bolt 19 adjustably anchored to the platform 13 through slot 80 18' in the latter.

85 A sliding carrier 20 is mounted in the slot 16 and has an upwardly projecting arm 21 located to be engaged by some part of the transerrer mechanism T at the time 90 of transfer to move said slide 20 forwardly. A weft detector 22 having a roughened surface 23 is mounted on a stud 24 projecting upwardly from the slide 20 and has detecting engagement with bobbin B in shuttle S.

95 A controller 25 is pivoted to a stud 26 carried by the bed 14 and has an upwardly projecting arm 27 normally in the position shown in full lines in Figs. 1 and 3 so as to be out of the path of the actuator lever 12. Said controller is provided with a counter-weight 28 which holds the controller normally in the position shown in Fig. 3. The casing and the matter thus far described as being associated therewith may be substantially the same as set forth in the aforesaid patent application and forms no part of my present invention.

In carrying my improvements into effect I provide the controller with a finger 40 which projects through a small slot 41 in the left hand depending wall 42 of the cap 15 and I further provide the detector member 22 with a forwardly projecting arm 43 having a left hand edge 44 for engagement with the right end of the finger 40 at the time of indication of weft exhaustion only. The slide 20 has struck upwardly therefrom a lug 45 which limits movement of the detector 22 around the stud 24 in a counter-clockwise direction. The forward end 46 of the arm 43 is bent upwardly slightly as indicated in Fig. 2 and is provided with a plurality of notches 47 each of which is proportioned to receive the forward end of a tension spring 48 the rear end of which is supported by a lug or stud 49 extending upwardly from the base 14.

Under normal conditions when sufficient yarn is present the detector will be moved forwardly without angular movement being held against the lug 45 by the spring 48 and under these conditions the left edge 44 of said detector will move past and clear of the finger 40 without moving the latter. When insufficient weft is present, however, the detector swings about the stud 24 in a clockwise direction to assume a position similar to that shown in Fig. 4, slide 20 under these conditions remaining substantially at rest and the controller 25 being moved from the full to the dotted line position shown in Fig. 3 to interrupt downward movement of the actuator lever 12 and thereby initiate a change in the operation of the loom. At the time of transfer the arm 21 is engaged by a part of the transferrer mechanism T and the slide 20 and detector member 22 will be moved forwardly so that the latter will be out of the path of the incoming bobbin.

From the foregoing it will be seen that I have provided a hollow casing which is closed substantially on all sides and that the controller finger 40 projects through the wall of the cap to be moved by the arm 43 of the detector. It will further be seen that a tension spring is employed to hold both the detector and slide yieldingly in rear position, a spring of this type being less hampered by contact with other parts and more readily assembled than is the case of

a compression spring. It will furthermore be seen that the extreme forward end of the detector member is provided with a series of notches which afford means for varying the pressure transmitted to the yarn by spring 48.

Having thus described my invention it will be seen that changes and modifications may be made therein by those skilled in the art without departing from the spirit and scope of the invention and I do not wish to be limited to the details herein disclosed, but what I claim is:

1. In weft detecting mechanism a substantially closed casing in which is slidably mounted a detector carrier, a side slipping weft detector pivotally supported by the slide, cooperating means formed on the detector and slide to limit angular movement of the detector with respect to the slide in one direction, an arm integral with the detector and extending forwardly and located within the casing, said arm being provided with a plurality of notches which are at different distances from the center of rotation of said detector, and a tension spring located within the casing and having one end fast with respect to the casing and having the other end held by one of the notches.

2. In weft detecting mechanism a substantially closed casing in which is slidably mounted a detector carrier, a side slipping weft detector means defining a pivotal connection between the detector and the slide, a portion of the detector resting directly on the slide and deriving its support therefrom, an arm formed integrally with the detector extending forwardly from the pivotal connection and bent upwardly to lie above the slide, stop means between the slide and the detector to limit angular movement of the latter in one direction, and a tension spring having one end fast with respect to the casing and having one end extending over the slide and connected to the upwardly bent end of the aforesaid arm, said spring holding the detector in normal position relatively to the slide and yielding when the slide and detector move forwardly while detecting a sufficient supply of weft.

In testimony whereof I have hereunto affixed my signature.

KENNETH J. UNWIN.
